UNITED STATES PATENT OFFICE

HENRY W. O'DOWD, OF JERSEY CITY, NEW JERSEY, ASSIGNOR TO STANDARD GAS EQUIPMENT CORPORATION, A CORPORATION OF MARYLAND

DESIGN FOR A GAS RANGE

Application filed November 30, 1931. Serial No. 41,916. Term of patent 14 years.

To all whom it may concern:

Be it known that I, HENRY W. O'Dowd, a citizen of the United States, residing at Jersey City, in the county of Hudson and State of New Jersey, have invented a new, original, and ornamental Design for a Gas Range, of which the following is a specification, reference being had to the accompanying drawing, forming a part thereof, and in which the figure is a perspective view of a gas range showing my new design.

As shown in the drawing the design presents a gas range with a fixed flat top section surmounting the oven, a hinged flat top section surmounting the cooking top and dis-

posed at a lower level with reference to the fixed section, and a mantel back rising from the two top sections and presenting an upper edge which slopes downwardly in a uniform manner from the center of the mantel toward its opposite ends and which is equipped at the center with an oval-shaped open work grating.

I claim:

The ornamental design for a gas range substantially as shown and described.

In testimony whereof, I have affixed my signature hereto.

HENRY W. O'DOWD.
